HEAD REST FOR DENTAL CHAIRS

Kenneth C. Kerr, 1222 S. Riverside, Medford, Oreg.

Filed Mar. 14, 1960, Ser. No. 59,711

Term of patent 14 years

(Cl. D15—8)

Fig. 1

Fig. 2

Fig. 4

Fig. 3

Fig. 5

FIGURE 1 is a perspective view of a head rest for dental chairs showing my new design;

FIGURE 2 is a top plan view of said new design;

FIGURE 3 is a left side elevational view thereof;

FIGURE 4 is a front elevational view of the design; and

FIGURE 5 is a rear elevational view of the design.

I claim:

The ornamental design for a head rest for dental chairs, as shown.
